(57) **CLAIM**

The ornamental design for a fragrance emanation device with car vent clip and visor clip, as shown and described.

DESCRIPTION

FIG. 1 is a front perspective view of a fragrance emanation device with car vent clip and visor clip according to our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the fragrance emanation device with car vent clip and visor clip of FIG. 1 in a visor-clip-open configuration;

FIG. 9 is a rear elevation view thereof in the visor-clip-open configuration;

FIG. 10 is a left side elevation view thereof in the visor-clip-open configuration;

FIG. 11 is a right side elevation view thereof in the visor-clip-open configuration;

FIG. 12 is a top plan view thereof in the visor-clip-open configuration;

FIG. 13 is a bottom plan view thereof in the visor-clip-open configuration;

FIG. 14 is a front perspective view of the fragrance emanation device with car vent clip and visor clip of FIG. 1 in a vent-clip-open configuration;

FIG. 15 is a rear elevation view thereof in the vent-clip-open configuration;

FIG. 16 is a right side elevation view thereof in the vent-clip-open configuration;

(Continued)

FIG. 17 is a top plan view thereof in the vent-clip-open configuration;
FIG. 18 is a bottom plan view thereof in the vent-clip-open configuration;
FIG. 19 is a front perspective view of the fragrance emanation device with car vent clip and visor clip of FIG. 1 in an open-body configuration; and,
FIG. 20 is a right side elevation view thereof in the open-body configuration.
The broken lines illustrate portions of the fragrance emanation device with car vent clip and visor clip that form no part of the claim.
